UNITED STATES PATENT OFFICE.

HARRY T. ANDERSON, OF BUTLER, PENNSYLVANIA, ASSIGNOR TO STANDARD STEEL
CAR CO., OF PITTSBURGH, PENNSYLVANIA, A CORPORATION OF PENNSYLVANIA.

SIDE-DUMP CAR.

1,237,445.

Specification of Letters Patent. Patented Aug. 21, 1917.

Application filed December 12, 1911. Serial No. 665,369.

To all whom it may concern:

Be it known that I, HARRY T. ANDERSON, a citizen of the United States, and resident of Butler, in the county of Butler and State 5 of Pennsylvania, have invented a new and useful Improvement in Side-Dump Cars; and I do hereby declare the following to be a full, clear, and exact description thereof.

My invention relates to side dump steel 10 cars, and more particularly to a type of cars having inclined hopper sheets leading from the center of the car toward the sides, to the support of the car body in this type of car, and to the mounting and operation of the 15 car door mechanism for the door as located at the side of the car. One desirable form of this car has doors of practically equal length extending along the sides and past the point where the car body is mounted on 20 the bolsters, and part of my invention relates to the construction of the car body to carry the load with cars having such doors. The invention also comprises different improvements relating more particularly to 25 this class of car as hereafter described and claimed.

In the accompanying drawings Figure 1 is a side view of the car. Fig. 2 is a longitudinal central section showing the mounting 30 of the sheaves which are illustrated in full lines. Fig. 3 is a top or plan view of a car. Fig. 4 is a plan view with the bottom hopper plates removed to illustrate parts thereunder. Fig. 5 is a cross section on the line 35 5—5 Fig. 1. Fig. 6 is a cross section on the line 6—6 Fig. 2 showing the car door operating mechanism in position. Fig. 7 is a like view with the car door operating mechanism removed; and Fig. 8 is a detail perspective illustrating the construction of the 40 hood and connecting parts.

The car is provided with suitable center sills which are illustrated as channel center sills at 2 extending through the length of the 45 car and around which is built the bolster which is formed of a center diaphragm 3 and side diaphragms 4 with the bottom strap member 5 extending across below the center sills and connected to the diaphragms 4; the center plates 6 being located under the 50 bolster. The car has the end sills 7 connected to the body portion and the vertical end wall 8 extending up to the top of the car. Suitable transoms 9 are also secured to 55 the center sill and extend out toward the

car sides. The car sides 10 are of plate girder type having the top angle chords 11, and the bottom chords 12 which, as illustrated in the cross sectional views, are of obtuse Z-bar form being so constructed for the 60 purpose hereafter described. The vertical members 10' by which said car side are formed into plate girders are located within the car body, as hereafter described, so that the outer car sides are flush, thus increasing 65 the capacity of the car. The car is provided with the end inclined hopper portions 13 which extend from the end walls at a downward incline and are riveted to the inclined bottom sheets. These inclined bottom 70 sheets 15 extend from the mid portion of the car body on a suitable incline and are connected at the top by the apex member 16 formed of an angle bar extending over and riveted to the top edges of the hopper sheets 75 15 and the hopper sheets are supported by both the bolster and end car construction and the cross hood construction, as hereafter referred to.

As shown particularly in Figs. 1 and 2 80 the doors near the end of the car extend from the end car construction past the bolster to the next cross hood and this requires a peculiar construction and system of support between the center sill and car sides, 85 the end portions of the car sides being supported by the end sill construction, the car sides being connected to said end portions and the next point of support for the car sides being found in the hood construction 90 beyond the bolster. In the mid portion of the car the doors are located between and joining the hood portions and the sheaves of the car door operating mechanism are located within such hoods and under the inclined end hopper portion 13, the load on 95 sides of cars being thus primarily sustained by the side and transmitted from the end sill construction and the next adjacent cross hood construction of the center sill and 100 thence back to the bolster. The other cross hood constructions also serve to give support to the car sides and carry it to the center sills through which the load is carried to the bolster below the car sides with space between the car sides exposed at the sides of the car, thus giving access to the car door mechanism as shown in Fig. 1 and also illustrated in the other sectional views.

As shown in Fig. 6 support is given to the 110

inclined hopper sheets at the bolster by means of the triangular diaphragm plate 17 which extends across above the center sill cover plate 18 and has the flange 19 riveted to the upper flanges of the bolster diaphragms 4 and the top flanges of the center sill and have also the flanges 20 extending under and riveted to the inclined hopper sheets 15, full support being thus given to the inclined hopper plates above the bolsters. The bolster diaphragms 4 have flanges only on three sides, the outer edges of such bolster diaphragms being inclined corresponding to the incline of the hopper plates and being connected thereto by angles 21 which are also secured to the hopper plates and which extend down to the lower edge of the door opening, being riveted to the longitudinally extending car members 22. These car members are formed of offset bars to stiffen them, that is, the body of the bar is riveted to the angle 21 of bolster construction and to the hopper plate at its lower edge and the bar is then off-set downwardly as at 23 and then extends at about the same downward incline as the upper portion of the bar to form the discharge lip 24 of the hopper, the off-set 23 in addition to stiffening the bar acting as a stop shoulder for the door. This off-set bottom car member in connection with the Z-bar 12 extends at the bottom of the car side and through the cross hoods acting as a secondary girder around the door openings.

The transoms at the cross chords are largely of the same construction as the bolsters having the center diaphragm 26, the side diaphragms 27, which as shown have flanges on three sides, the transom members, however, being of greater length than the bolster members 4, the end portions 28 of the webs thereof extending out and lapping over the hood plates 29 as well illustrated in Fig. 8. The inclined hopper plates 15 extend between the cross hoods and between the outer cross hood and the end of the car, and the cross hoods having flanges 30 fitted below the inclined plates and riveted thereto. The inclined hopper plates also are supported from the transoms by means of the center pedestal 31 which rests upon and is riveted to the center sill cover plate 18 and extends up toward the apex of the inclined bottom and has flanges 32 riveted to the upper portions of the inclined hopper plates. The cross hoods 29 extend up for practically the full length of the inclined hopper plates, their upper portions 33 being inwardly inclined and the flange 30 being correspondingly bent as at 34 to fit the top portion of the inclined hopper plates. At the top edge of the roof portions 33 of the hoods are flanges 35 which are riveted to each other with vertical cross plates 36 fitted in between and riveted to said flanges, said vertical cross plates being braced at their top edges by the cross angles 37 which extend entirely across the car body, said angles having flanged edge portions 38 riveted at the top and bottom of the angles to the cross plates and said cross angles thus bracing the car extending over and being riveted to the car sides 10. In this way the car sides are braced by the entire construction of the hood including the cross angles 37. Flanged gusset plates 40 are carried from the angle bars 37 up to the top chords 11, such gusset plates being riveted to the flanges 38 of the cross angles and their inner edges being flanged at 41 and riveted to the car sides, thus continuing the vertical stiffeners formed by the vertical hood members 29 up to the top chord members, and said hood members are bent at their lower ends in shape to correspond to the obtuse Z-bar bottom chords 12 of the car sides. The car sides have also additional vertical stiffeners 42 formed at intermediate points, for example in line with the bolsters and about mid-way between the hood and end portion of the car as shown in Fig. 2, the intermediate stiffeners extending between the top and bottom chords 11 and 12 of the car sides.

It will thus be seen that the load is carried principally by the center sill which supports the car sides over the bolster between the ends of the car to the next adjacent cross hood, the car sides being securely connected to the hood members through the cross angles 37 and the cross plates 36 and the entire cross hood construction, the bolsters being thus bridged and the load transmitted to them not only through the center sills, but by the triangular diaphragm 17 directly above the bolsters and by the inclined hopper plates resting on and secured thereto.

The car doors are formed of flanged plates 45 of proper size having the top flanges 46, the bottom flanges 47 and edge flanges 48. They are hinged to bracket castings 49 secured on the outside of the obtuse Z-bar bottom chords 12, the upper ends of the doors being located under said Z-bar chords, while their lower edges when closed contact with the off-set bars 22 secured at the base of the inclined hopper plates 15, the off-sets 23 of said bars forming the abutments against which the doors close. Extending the full length of the car are the channel bars 50 by which the doors are opened and closed, said bars extending across the open ends of the hoods and the door operating mechanism being connected to said channel bars in said space.

While any suitable character of door operating mechanism may be employed I prefer and have illustrated substantially the mechanism of Letters Patent No. 616,811, granted to Simonton, December 27, 1898, the same

being modified to suit the conditios of use. For operating the doors I provide the main center operating shaft 53 mounted centrally of the car directly under the apex 16 and 5 under the inclined hopper plates and under the hopper plates in the different cross members, for example extending through journal bearings secured to the end wall 8 of the car, the center diaphragm 17 above the bolsters 10 and the pedestals 31, the shaft having ratchet and pawl mechanism 54 at the end of the car. This shaft carries a series of chain sheaves 55, 56, at the ends of the car, and 57 and 58 at each cross hood. As more 15 clearly shown in Fig. 5, mounted in suitable bearings on the transoms 27 at the hoods and like transoms 59 and 60 at the ends of the car are the sheave levers 61 at the hoods and 62 at the end of the car, these sheave 20 levers being substantially the same in construction as shown in said Simonton patent, having pivots 63 and straight bearing faces 64, links 65 being pivoted at 63, the operating bars 66 having hooks 67 at their upper 25 ends leading from abutments 68 on the sheave levers, said hooked arms 66 extending out and being connected by clevises 70 to the longitudinally extending channel bars 50 connected to the doors. Each central 30 chain sheave mounted on the shaft 53 is connected by chains to a sheave lever on each side of the car. For example at the cross hood the sheave 58 as illustrated in Fig. 5 is connected by the chain 72 on one side of 35 the sheave lever to the right of said lever, the chain being positively connected to both the central sheave and the sheave lever and acting on the turning of the central shaft to close the door by turning the sheave to 40 the left in which case the link 65 fits against one side of the abutments 68 and as the sheave is turned further the hooked arm 67 fits over said abutment and rests against the face 64 and the door is thus drawn close. 45 For convenient illustration the doors are shown as open on the right of Fig. 5 and closed on the left thereof, it of course being understood that the door operating mechanism does not in practice permit of this 50 relative position but that the doors are so mounted that the turning of the main shaft 53 operates to open the doors on each side of the car simultaneously and to close them simultaneously. Carried from the same 55 sheave is the chain 74 connected to the sheave lever on the other side of the car so that when the sheave lever is turned in the proper direction for closing both doors will be closed at the same time. In like manner 60 chains 73 and 75 are connected to the sheave 57 on the central shaft and extend to the two sheave levers so that by the turning of the central shaft in the opposite direction the sheave levers are turned back by the pull 65 of those chains to cause the opening of the

doors, as shown to the right of Fig. 5. In the use of this type of door operating apparatus in side door cars such as those illustrated, it is important that means be provided to hold the doors open and at the same 70 time to stop the movement of the parts when the doors have reached their farthest outward swing. To that end the links 65 are provided with shoulder lugs 76 which, when the door is forced out to the full extent desired, contact with the hooked ends 67 of the arms 66 and by contact therewith prevent further turning of the main operating shaft by stopping the further movement of the sheave levers and holding the doors in 75 outward position until the shafts are turned in the opposite direction to close the doors as herein described.

It will be noticed that to give the above 80 operation, the chains on one side of the car such as those leading from the chain shaft 58 are crossed. This is necessary to cause the simultaneous opening and closing of the doors through the turning of the sheave levers as above described, and to get the 85 necessary movement while turning the main shaft and its chain shafts in the same direction.

Practical use has shown that the above 90 car door operating mechanism is very efficient in providing for the simultaneous opening and closing of the doors throughout the length of the car and accomplishing this without any great strain upon the operating shaft or the other operating parts as the 95 connection with the chain on both sides of the sheave levers and operating in both directions therefrom provides for distributing this strain throughout the entire length of the car and the simultaneous drawing of all 100 doors to closed or opened position.

What I claim is:

1. A car having a center sill, a bolster built around the same, an end construction and a hood construction on the other side of the bolster, both connected to the center sill, and inclined hopper plates over the center sill extending from the end of the car over the bolster to said hood.
2. A car having a center sill, a bolster built around the same, an end construction and a hood construction on the other side of the bolster, both connected to the center sill, inclined hopper plates over the center sill extending from the end of the car over the bolster to said hood, and a center support above the bolster and extending up and secured to the inclined hopper sheets.
3. A car having a center sill, a bolster built around the same, an end construction and a hood construction on the other side of the bolster, both connected to the center sill, inclined hopper plates over the center sill extending from the end of the car over the bolster to said hood, a triangular dia-

phragm secured centrally above the bolster and extending up to and riveted to the end faces of the inclined hopper sheets.

4. A car having a center sill, a bolster built around the same, an end construction, and a hood construction on the other side of the bolster, both connected to the center sill, inclined hopper plates over the center sill extending from the end of the car over the bolster to said hood, and car sides extending from the car end past said bolster to said hood and connected to the end construction and said hood.

5. A car having a center sill, an end construction secured thereto, a bolster, a hood construction connected to the center sill beyond the bolster, car sides extending from the end past the bolster to the hood and connected to the hood, said car sides being of plate girder construction, hopper sheets extending at a downward incline from the mid-portion of the car below the car sides, and doors hinged to the car sides and extending down to the base of the hopper sheets.

6. A side dump hopper car having a series of cross hoods, hopper sheets extending between them from the mid portion of the car body at a downward and outward incline, car sides above the discharge openings, doors hinged at the base of the car sides and having connecting bars common to two or more doors, door operating mechanism within the hoods and connected to said bars, and a continuous bar at the base of the hopper sheets extending across the side openings of the hoods, such bottom bars being provided with an off-set forming a stop for the doors when closed.

40 7. A car having a center sill, cross hoods supported thereon, hopper sheets extending between the cross hoods from the center of the car at a downward and outward incline, and transoms connected to the center sill

and extending out and having their ends 45 lapping over and riveted to the hood bodies.

8. A car having a center sill, cross hoods supported thereon, hopper sheets extending between the cross hoods from the center of the car at a downward and outward incline, 50 and transoms connected to the center sill and extending out and having their ends lapping over and riveted to the hood bodies, and center pedestals resting on the center sills close to the transoms and extending 55 up and riveted to the hopper sheets.

9. A car having a center sill and cross hoods at intervals in the length of the car, and hopper sheets extending from the mid portion of the car at a downward and outward incline toward the sides between said hoods, said hoods each having two hood plates on each side of the center sill to which the hopper plates are connected at the bottom, said hood plates extending upwardly and thence by inward incline to a center cross plate above the hood, and car door mechanism mounted within such hood portions.

10. A car having a center sill and cross 70 hoods at intervals in the length of the car, and hopper sheets extending from the mid portion of the car at a downward and outward incline toward the sides between said hoods, said hoods each having two hood 75 plates on each side of the center sill to which the hopper plates are connected at the bottom, said hood plates extending upwardly and thence by inward incline to a center cross plate above the hood, and transoms extending out from the center sills and lapping over and riveted to the hoods.

In testimony whereof, I the said HARRY T. ANDERSON have hereunto set my hand.

HARRY T. ANDERSON.

Witnesses:

JAMES I. KAY,
ALVAR C. PURDY.
